UNITED STATES PATENT OFFICE.

LOUIS W. HASKELL, OF NEW YORK, N. Y., ASSIGNOR TO GENERAL FIRE EXTINGUISHER COMPANY, OF PROVIDENCE, RHODE ISLAND, A CORPORATION OF NEW YORK.

ANTIFREEZING MEANS FOR SPRINKLER-PIPES.

1,134,380.

Specification of Letters Patent.

Patented Apr. 6, 1915.

Application filed August 21, 1906. Serial No. 331,448.

To all whom it may concern:

Be it known that I, LOUIS W. HASKELL, a citizen of the United States of America, and a resident of the city, county, and State of New York, have invented certain new and useful Improvements in Antifreezing Means for Sprinkler-Pipes, of which the following is a specification.

My invention concerns certain new and useful improvement in means for preventing the water or other fluid from freezing in stationary sprinkling pipes, such as are commonly distributed throughout a building for fire protection, said pipes being provided with a series of sprinkler heads or nozzles which fuse at a certain point and open valves to let out the water supply for the purpose of extinguishing a conflagration. One of the great disadvantages in the use of a stationary fire engine of this kind (which has so many advantages and excellent results) is the freezing of the water when the temperature drops sufficiently low, whereby the pipes burst and the apparatus is damaged or ruined.

The object of my invention is to overcome this difficulty, and it consists essentially in suitable means for pumping or forcing warm or hot water, steam, or some other heating fluid into the pipes in such quantities as will maintain the temperature of the water in the pipes liable to freeze at a temperature above the freezing point and below the temperature at which the sprinkler head will open up by melting off the alloy fastening, it being understood that the injection of the proper quantity of hot or warm water, steam, or other heating fluid, will heat the water sufficiently to prevent freezing, but not so much as to melt the fusible part of the sprinkler nozzle; and the invention may also be said to consist in certain details and peculiarities of construction, arrangement and combination, substantially as will be hereinafter more fully described and then particularly pointed out in the claims.

In the annexed drawings Figure 1 is a top plan view of one form of a system of sprinkler piping provided with the usual nozzles and supposed to be arranged in conjunction with the ceiling of an apartment or room for the purpose of providing fire protection. Fig. 2 is a side view of the same. Fig. 3 is an enlarged sectional view of a

union or coupling for connecting the steam or hot water supply pipe with the end of one of the stationary cold water pipes.

Like numerals of reference denote like parts throughout the different figures of the drawing.

In portraying a system or portion of a system of stationary sprinkler pipes as I have done in the drawings herein, I do so simply to illustrate one way in which the invention may be practically applied, and with no thought of being confined to the particular arrangement shown, inasmuch as the anti-freezing means is adaptable for use with any combination of pipes or tubes, whether they be few or numerous, placed in any desired manner in a building, and it is obvious that the pipes and other connections and mode of arrangement, as well as the means for forcing the steam, hot water, or other heating fluid, may vary within very wide limits.

In the example of piping indicated in Fig. 1, I have shown a central water supply pipe 2, from both sides of which lead off the parallel pipes 1 which may be of the customary tapering variety, all these pipes 1 being provided at suitable intervals with sprinkler heads or nozzles 3 through which the water is released when the temperature incident to a blaze rises to a point where the fusible parts of these heads are melted. These various pipes are customarily supported in a horizontal position near the ceiling, in order that the water may be distributed freely over the room and its contents. Pipe 2 is called a header and is of large size so as to carry the water from the riser (not shown) to the branches 1. These branches are smaller than the header, and, as stated, they generally reduce in diameter from the point where they leave the header toward their outer ends. These are the pipes which hold the water and which when the temperature drops sufficiently low are liable to freeze and burst. The sprinkler heads 3 may vary widely in their construction and may be described as valves kept shut by a melting strip of alloy which melts at a fixed temperature, say about 160° F. In cold weather the water in the smaller pipes 1 freezes and bursts the pipes. When the weather becomes warmer the ice melts and the water runs out of the pipes. During all this time, the sprinkler system will be of no

value for extinguishing fires, thus an insurance company which has insured a building at a low rate on account of its being protected by sprinklers is really for a time at any rate carrying in effect a risk unprotected by any sprinkler system.

In order to prevent the water from freezing in the pipes 1, my invention consists in introducing into the terminals of all of these pipes 1 a quantity, preferably a small quantity, of hot or warm water, steam, or other heating fluid or agent, in order that the aqueous contents of the pipes 1 may be heated sufficiently to prevent them from freezing; but, obviously, as I have already said, the steam or hot water, or other heating fluid or agent so introduced must not be sufficiently hot to cause any melting of the sprinkler heads, for that would defeat the beneficial purpose of the invention. The supply of steam, hot water, warm water, or other heating fluid or agent to be used for this purpose, may come from any suitable source, as, for instance, a boiler 15. From this boiler runs a pipe 14. Near the ends of the sprinkler pipes 1 I arrange hot water supply pipes 4, the same being connected together by a pipe 18, while the boiler pipe 14 enters one end of one of the pipes 4. One end of each of the sprinkler pipes 1 is connected with one of the hot water pipes 4 by means of a suitable union or coupling, an example of which is shown in Fig. 3 and also at 7 in Fig. 2.

35 The hollow cylindrical body of the union consists preferably of two pipe sections 22 and 23. A diaphragm 20 having a hole 21 at the center and consisting of a metallic circular disk is clamped between the pipe sections 22 and 23. This is a common form of union and is offered here simply to assist in the explanation and as furnishing one form of device for enabling the hot water to be introduced from the hot water pipes into the sprinkler pipes. The central opening or orifice 21 in the diaphragm 20 is sufficiently minute to allow the steam or hot water to pass through comparatively slowly. When pumping or forcing means are employed to drive the hot water through the perforated diaphragm 20 it will mingle with the cold water in the pipes 1, heating it to the proper degree to prevent freezing.

55 Obviously the size of the opening 21 in the diaphragm must bear a definite ratio to the bore of the hot water supply pipe, in order that the proper quantity of hot water may be supplied to each of the sprinkler pipes 1. In other words, the size of the orifice 21 must be regulated in correspondence with the supply of hot water or steam, so that there may be ample hot water or steam to supply all the sprinkler pipes with an equal quantity of hot water or steam, and so that no sprinkler pipe will get an excess-

sive quantity of hot water or steam. The size of the openings 21 must be such that the supply of hot water will be distributed in about equal quantities through all such openings. This may be accomplished by 70 making the sum of the areas of all the openings 21 less than the area of the supply pipe feeding these openings.

In forcing the hot water into the sprinkler pipes, it is to be remembered first that the 75 supply of hot water must be sufficient to warm the water in the pipes liable to freeze; second, the water must not be too hot or it will melt the strip of alloy which holds the small sprinkler valve (commonly called the 80 sprinkler head) closed, which head is only to be discharged by a fire in the building; third, the water must be put into all the 85 sprinkler pipes at approximately the same temperature and in about the same quantity. Hence, it will be understood that the 90 temperature, quantity and distribution of the water forced into the pipes must be regulated. The hot water pipe 4 which is connected to the small end of each branch pipe 95 1 is generally larger in diameter than the small ends of the branch sprinkler pipes, and for this reason it must be manifest that unless the water supply is regulated the first two branch sprinkler pipes will be likely to 95 take all the water supplied through the hot water pipe. Furthermore, it will be found necessary to provide means for taking care at some suitable point of a certain amount of water which is in the sprinkler pipes, in 100 order that it may be possible to introduce the extra hot water or steam, but in practice this will be an easy thing to accomplish for it will only be necessary to place an outlet valve in some part of the system to do this 105 work.

In practising the invention, the janitor or attendant when he finds that the temperature of the atmosphere is dropping to near the freezing point, or below it, and that 110 there is danger of the water freezing in the pipes, will pump or otherwise force or introduce the required amount of hot water into the ends of the branch sprinkler pipes, or will introduce a certain amount of steam 115 or other heating fluid or agent, thus preventing freezing and enabling the desirable results proposed by this invention to be easily and speedily accomplished. It is only necessary, in order to carry out the purposes of this invention, that the passages between the hot water supply pipe and the ends of the branch sprinkler pipes should at a certain point be constricted sufficiently 120 to allow only the right amount of hot water to pass through, and this constriction may be obtained by the use of a perforated diaphragm or any other suitable equivalent means. The hot water, when it passes 125 through the constricted delivery and enters 130

the branch sprinkler pipes, mingles with cooler water which, however, gradually warms up from the increasing supply of warm water, while the hot water is also cooled down by the surrounding atmosphere. There are two ways of regulating the temperature in the branch sprinkler pipe. First, by the temperature of the water in the hot water supply pipe, and second, by 10 the size of the orifice between the hot water supply pipe and the branch sprinkler pipe. The size of the orifice between the hot water supply pipe and the branch sprinkler pipe is therefore not entirely regulated by the 15 distribution feature, but also by the amount of hot water to be introduced into each branch sprinkler pipe; but when it is remembered that the range of temperature in the branch sprinkler pipe may be any way 20 between 40° F. and 140° F. with equally good results, it will be seen that this is not a difficult problem, and can be easily regulated to meet conditions. The degree of pressure in the hot water supply pipe also 25 is a factor in regulating the proper amount of distribution.

Having thus described my invention, what I claim as new and desire to secure by Letters Patent, is:

30 1. In an automatic fire extinguishing apparatus, the combination of a system of sprinkler pipes provided with automatic sprinkler heads and each in open communication at one end with a water supply main, 35 whereby the pipes are normally kept filled with water under the service pressure, a supplementary supply pipe and connections between the same and the opposite ends of the several sprinkler pipes, and means for 40 forcing a heated fluid into the supplementary supply pipe and thence into the sprinkler pipes against the service pressure therein.

2. In an automatic fire extinguishing apparatus, the combination of a system of 45 sprinkler pipes provided with automatic sprinkler heads and each in open communication at one end with a water supply main, whereby the pipes are normally kept filled with water under the service pressure, a 50 supplementary supply pipe and connections between the same and the opposite ends of the several sprinkler pipes, means for forcing a heating fluid into the supplementary supply pipe and thence into the sprinkler 55 pipes against the service pressure therein, and flow-choking devices included in said connections and having such capacity as to insure the distribution of the heating fluid among the several sprinkler pipes. 60

3. In an automatic fire extinguishing apparatus, the combination of a system of 65 sprinkler pipes provided with automatic sprinkler heads and each in open communication at one end with a water supply main, whereby the pipes are normally kept filled with water under the service pressure a supplementary supply pipe and connections between the same and the opposite ends of the several sprinkler pipes, and means for forcing a heating fluid into the supplementary supply pipe and thence into the sprinkler pipes against the service pressure therein, each of said connections being provided with a flow-choking device consisting of a 75 wall having therein a perforation of such size that the aggregate capacity of the perforations is sufficiently limited to insure the distribution of the heating fluid among the several sprinkler pipes. 80

Signed at New York city this 14th day of August, 1906.

LOUIS W. HASKELL.
